UNITED STATES PATENT OFFICE

157,210

APPLIQUÉ OR THE LIKE

Morris Silberman, New York, N. Y., assignor to Moses Streesover, New York, N. Y.

Application December 13, 1947, Serial No. 143,131

Term of patent 3½ years

(Cl. D3—9)

To all whom it may concern:

Be it known that I, Morris Silberman, a citizen of the United States of America, residing in the city of New York, county of Kings, and State of New York, have invented a new, original, and ornamental Design for an Appliqué or the like, of which the following is a specification, reference being had to the accompanying drawing, forming part thereof, wherein the figure is a plan view of an appliqué showing my new design.

I claim:

The ornamental design for an appliqué or the like, substantially as shown.

MORRIS SILBERMAN.
